RECEPTACLE AND CLOSURE

William Lockhart, Cleveland, Ohio, assignor to
 Cornell Securities Corporation, Cleveland,
 Ohio, a corporation of Delaware

Application May 3, 1935, Serial No. 19,642

7 Claims. (Cl. 220—61)

My invention is an improvement in devices for removably clamping a cover on a metallic receptacle such as shipping drums, barrels or the like of heavy gauge material and relates more particularly to a clamping ring and means for expanding and/or contracting the same for removing or securing the cover on a drum in fluid tight sealed relation thereto.

One of the objects of my invention is to provide a ring contracting and/or expanding mechanism capable of applying successive contracting forces of increased intensity to the ring to contract the same and to thereby press the cover and receptacle together in fluid tight sealed relation.

Another object is to construct such a device which is self-contained within the confines of the ring and which includes a pair of operating levers swingable in opposite directions to contract the ring.

A further object is to provide means for contracting the ring whereby the ring may be initially contracted to firmly secure the cover in place on the receptacle for shipping the same empty, and whereby the ring may be further contracted to effectively seal the cover on the receptacle in fluid tight relation, said means being capable of operation so as to apply said contracting forces either simultaneously or successively.

A still further object consists in providing a bearing member operable by a pair of levers to impart an outward substantially radial pressure against the cover flange to draw the ring ends inwardly toward the cover flange and receptacle and together, whereby the contracting forces applied to the ring will be more uniformly distributed about the circumference of the ring.

Another object consists in providing a device of the character described which is very strong and durable, and which is capable of exerting tremendous closing pressures on the cover and drum, yet which is simple of construction and assembly and very inexpensive to manufacture.

Other objects and advantages of the invention will become more apparent from the following description of one embodiment thereof, reference being made to the accompanying drawing in which like reference characters are employed to designate like parts throughout the same.

In the drawing:—

Figure 1 is a top plan view of an embodiment 55 of my invention shown applied in use;

Figure 2 is an enlarged section taken on line 2—2 of Figure 1.

Figure 3 is a fragmentary view of the device applied in use and shows the positions of the levers and other parts when the ring is fully contracted;

Figure 4 is a view similar to that shown in Figure 3 and shows the parts in position when the ring is fully expanded to remove the ring and cover from the receptacle;

Figure 5 is a slightly enlarged view looking in the direction of line 5—5 of Figure 3;

Figure 6 is an enlarged section taken on line 6—6 of Figure 1; and

Figure 7 is a section taken on line 7—7 of 15 Figure 3.

Referring now more particularly to the drawing, the barrel or drum is indicated at 1. The upper open end of the container is formed with a peripheral bead 2. A cover 3 comprising a 20 cupped or depressed member, having a peripheral upwardly and outwardly extending flange 4, is supported by the bead 2 in such a manner that the cupped portion of the cover may be telescoped for a short distance within the open end 25 of the container, as illustrated in Figure 2. It will be noted that a portion of the flange 4 is of arcuate cross section to conform with the approximate curvature of the upper surface of the bead. A packing 5 consisting of an annulus of 30 any suitable packing material, such as flexible rubber tubing or cork, is interposed between the flange 4 and the bead.

According to the present invention, I have provided an extremely simple and efficient means 35 for removably securing the cover on the receptacle or container to effect a fluid tight seal between the same by exerting a substantially uniform and firm pressure along the cover flange and bead in a direction substantially parallel to 40 the axis of the container.

Such means preferably includes a transversely split, channeled clamping ring 6 of substantially U-shaped cross-section and which is capable of being contracted and expanded by suitable 45 means. In the form illustrated the upper and lower flange and bead engaging walls respectively of the ring converge outwardly and engage the cover flange and bead of the container to press the same together tightly when the ring 50 is contracted. However, it is to be understood that the ring and receptacle open and may be so designed that the cover will be pressed into a tight seal with a shoulder at the receptacle open end when the ring is expanded.

Upon contracting the type of ring herein illustrated it will be seen that the cover flange will be tightly pressed against the packing 5 and the supporting bead 2 under a substantially 5 vertical pressure.

The ring is provided at its ends with suitable lugs, plates, or the like, 7 and 8, which are preferably welded to the adjacent ring ends respectively and extend inwardly of the ring to 10 movably support suitable means for contracting and expanding the ring.

Operating levers 9 and 10 are pivotally connected with the respective lugs or brackets 7 and 8 at 11 and 12, and are mounted to swing 15 within the confines of the ring.

These levers are connected together in substantially parallel planes by a sort of toggle or multiple link to provide an effective power driving connection therebetween comprising two 20 sets of links 13-14 and 15-16, one set 13-14 lying in a plane above that of the levers and the other set 15 and 16 lying in a plane below that of the links. An additional link 17 also pivotally connects the underside of the lever 10 25 with the lug 8 and affords additional reinforcement and balance to the lever 10.

A stud or rivet 18 pivotally connects adjacent ends of the respective links 13, 14, 15 and 16 as shown more clearly in Figure 5, and is slide- 30 able along the slot 19 cut in the lug 7. The opposite respective ends of the links 13 and 15 are pivotally connected to the lever 9 by means of the stud or rivet 20, while the other ends of the respective links 14 and 16 are pivotally connected with the lever 10 by means of the stud 21. The opposite end of the reinforcing link 17 is likewise pivotally connected with the stud 21.

It is to be noted that the links 13 and 15 are shorter than the links 14 and 16 and that they 40 are pivoted to the lever 9 at a point defining a shorter radius (between the axes 11 and 20) than the radius defined by the axes 12 and 21 on the lever 10. By means of this construction the lever 10 may first be swung to the right 45 in Figure 4 to impart an initial degree of contraction to the ring which will be sufficient to hold the cover in place as in shipping the drums empty. In so doing the stud 18 will travel to the right in the slot 19 until it abuts the wall at 50 the right hand end of the slot. Further movement of the lever 10 to the right will draw the ends of the ring toward each other to initially contract the ring. Movement of the lever 9 in the opposite direction about its pivot 11 will 55 effect a driving connection through the shorter radius 11-20 to apply additional power in further contracting the ring to seal the cover on the receptacle end in fluid tight sealed relation. As the lever 9 approaches the circumference of 60 the ring in its movement to the left the linkage 13, 14, 15 and 16 will have relative movement with the lug 7 and the stud 18 will slide in the slot to a point intermediate the slot ends as shown in Figure 3.

It will be seen that I have also provided a 65 cam-like bearing surface 22 by extending the outer edge of the lower link 16 toward the circumference of the ring. This bearing surface 22 is curved and is positioned to engage the inner upright wall of the cover flange 4 when the lever 10 is rotated to the right to exert an 70 outward substantially radial pressure against the cover flange adjacent the split, whereby the ends of the ring will be pulled inwardly toward 75 the axis of the receptacle. This action mate-

rially aids in uniformly distributing the closing forces about the circumference of the ring during contraction of the same and further assists in properly seating the ring on the bead and cover flange. 5

Suitable keepers or retainers 23 and 24 may be welded to the ring at points to receive the handle portions of the levers 9 and 10 respectively and to removably retain them in ring contracted position. Registering openings 25 and 26 in the 10 levers and retainers will permit the levers to be inspection sealed in the usual manner.

While I have described the illustrated embodiment of my invention in some particularity, obviously many others will readily occur to those skilled in this art, and I do not, therefore, limit myself to the precise details shown and described but claim as my invention all embodiments, variations and modifications thereof coming within the scope of the appended claims. 20

I claim:

1. In a clamping device for a metallic receptacle having a bead formed on its open end and a cover having a flange fitting over the bead, a contractible channeled clamping ring having portions engageable with and pressing the cover flange and bead together when the ring is contracted, lugs extending inwardly of the ring from the ends thereof, and means for contracting the ring including levers pivotally connected with each of said lugs, and means connecting said levers to provide a driving connection therebetween, one of said lugs having a guide to receive and guide said connecting means during swinging movement of either of said levers. 30

2. In a clamping device for a metallic receptacle having a bead formed on its open end and a cover having a flange fitting over the bead, a contractible channeled clamping ring having portions engageable with and pressing the cover flange and bead together when the ring is contracted, lugs extending inwardly of the ring from the ends thereof, and means for contracting the ring including levers pivotally connected with each of said lugs, and means connecting said levers to provide a driving connection therebetween, one of said lugs being slotted to receive and guide a portion of said connecting means during rotation of either of said levers. 40

3. In a clamping device for a metallic receptacle having a bead formed on its open end and a cover having a flange fitting over the bead, a contractible channeled clamping ring having portions engageable with and pressing the cover flange and bead together when the ring is contracted, lugs extending inwardly of the ring from the ends thereof, and means for contracting the ring including levers pivotally connected with each of said lugs, and means connecting said levers to provide a driving connection therebetween, one of said lugs being adapted to positively receive and guide said connecting means during rotation of either of said levers, and a projection on said connecting means for bearing against the cover flange when one of said levers 50 is rotated to exert a substantially radial outward pressure against the cover flange. 55

4. In a clamping device for a metallic receptacle having a bead formed on its open end and a cover having a flange fitting over the bead, a 70 contractible channeled clamping ring having portions engageable with and pressing the cover flange and bead together when the ring is contracted, lugs extending inwardly of the ring from the ends thereof, and means for contracting 75

the ring including levers pivotally connected with each of said lugs, and means connecting said levers to provide a driving connection therebetween, one of said lugs being slotted to receive and guide a portion of said connecting means during rotation of either of said levers, and a projection on said connecting means for bearing against the cover flange when one of said levers is rotated to exert a substantially 10 radial outward pressure against the cover flange.

5. In a clamping device for a metallic receptacle having a bead formed on its open end and a cover having a flange fitting over the bead, a contractible channeled clamping ring having 15 portions engageable with and pressing the cover flange and bead together when the ring is contracted, lugs extending inwardly of the ring from the ends thereof, and means for contracting the ring including levers pivotally connected with each of said lugs, a pair of links pivotally connecting said levers to provide a driving connection therebetween, a bearing member carried by 20 said links, one of said lugs being formed to slidably receive said bearing member and to limit its movement in one direction whereby the ends of the ring may be drawn together when one of said levers is rotated.

6. In a clamping device for a metallic receptacle having a bead formed on its open end and 30 a cover having a flange fitting over the bead, a contractible channeled clamping ring having portions engageable with and pressing the cover

flange and bead together when the ring is contracted, lugs extending inwardly of the ring from the ends thereof, and means for contracting the ring including levers pivotally connected with each of said lugs, a pair of links pivotally connecting said levers to provide a driving connection therebetween, a bearing member carried by 5 said links, one of said lugs being slotted to slidably receive said bearing member and to limit its movement in one direction whereby the ends of the ring may be drawn together when one of said levers is rotated.

7. In a clamping device for a metallic receptacle having a bead formed on its open end and 10 a cover having a flange fitting over the bead, a contractible channeled clamping ring having 15 portions engageable with and pressing the cover flange and bead together when the ring is contracted, lugs extending inwardly of the ring from 20 the ends thereof, and means for contracting the ring including levers pivotally connected with each of said lugs, a pair of links pivotally connecting said levers to provide a driving connection therebetween, a bearing member carried 25 by said links, one of said lugs being formed to slidably receive said bearing member and to limit its movement in one direction whereby the ends of the ring may be drawn together when one of said levers is rotated, one of said 30 links being shorter than said other link.

WILLIAM LOCKHART.
